(57) **CLAIM**

I claim the ornamental design for a hemostat style elongated dissecting and dividing instrument, as shown.

DESCRIPTION

FIG. 1 is a perspective view of a hemostat style elongated dissecting and dividing instrument showing my new design; FIG. 2 is a front view of the hemostat style elongated dissecting and dividing instrument of FIG. 1; FIG. 3 is a rear view of the hemostat style elongated dissecting and dividing instrument of FIG. 1; FIG. 4 is a left side view of the hemostat style elongated dissecting and dividing instrument of FIG. 1; FIG. 5 is a right side view of the hemostat style elongated dissecting and dividing instrument of FIG. 1; FIG. 6 is a top view of the hemostat style elongated dissecting and dividing instrument of FIG. 1; and, FIG. 7 is a bottom view of the hemostat style elongated dissecting and dividing instrument of FIG. 1.
